UNITED STATES PATENT OFFICE.

HENRY TAYLOR KING, OF SEDALIA, MISSOURI, ASSIGNOR OF ONE-HALF TO
JOHN F. ANTES, OF SAME PLACE.

FRUIT OR ICE CUTTER.

SPECIFICATION forming part of Letters Patent No. 410,900, dated September 10, 1889.

Application filed September 24, 1888. Serial No. 286,257. (No model.)

To all whom it may concern:

Be it known that I, HENRY TAYLOR KING, a citizen of the United States of America, residing at Sedalia, in the county of Pettis and

5 State of Missouri, have invented certain new and useful Improvements in Fruit or Ice Cutters, of which the following is a specification.

My invention relates to certain improvements in devices or machines for cutting fruit, 10 ice, &c.; and it consists in certain novel constructions and combinations of parts, as will be hereinafter described, and pointed out in the claims.

In the accompanying drawings, Figure 1 is 15 a top plan view of my invention; and Figs. 2 and 3 are cross-sectional views of front and rear parts of the same, taken through the lines $\alpha\alpha$ and yy , respectively, of Fig. 1. Fig. 4 is a sectional view of the same in side elevation. Fig. 5 is a view in elevation of the cutting-cylinder, conical-shaped; and Fig. 6 is a like view of the cylinder having parallel sides.

In the drawings, A represents the frame of 25 the machine, and B the cutting-cylinder, which may be made either parallel or conical-shaped, having a hollow interior and supported in a suitably-constructed frame.

1 is the front part and 2 the rear end of the 30 frame provided with suitably-constructed legs or base portion 3. These end parts are preferably provided with suitable grooves 4, flaring or diverging upwardly from each side of the lower part of the cylinder. The two 35 side portions 5, when placed in said grooves, are clamped therein by screw-rods 6, passing through holes 7 in the end parts 1 and 2; or any other suitable means may be employed for holding said parts together, forming a 40 flaring hopper 8, above and around the cutting-cylinder, as shown in Figs. 1, 2, 3, and 4.

The front part 1 of the frame is provided with a hole 9, through which the stem forming the front axis 10 of said cylinder passes, 45 and having a propelling-crank 11 attached to its outer end. The rear end 2 of said frame is also provided with a round opening 12, in size to admit the large end 13 of the cylinder to pass through and rotate therein.

50 15 is a suitable band or collar, which is placed around the outer part of the rear end

of the cylinder and adapted to bear against the inner side surface of the end-frame part 2, preventing lateral play of said cylinder when rotating upon its axis.

55

The cylinder B may be formed of longitudinal sections or by bending a single piece of sheet metal or steel having its two ends united together, forming a hollow tube, either parallel or conical-shaped, as shown.

60

The front end of the cylinder is provided with a gudgeon or axis 10, having an enlarged inner end formed into a flange or rim 17, fitting into the cylinder and riveted or otherwise connecting the parts together, forming 65 the cylinder B, as shown in the drawings, Figs. 1, 5, and 6.

I prefer using sheet-steel in the construction of said cylinder, and form the cutting-knives 16 integral therewith by the use of 70 suitably-shaped tools or dies adapted to the purpose, which are made to cut through the metal of which the cylinder is made, raising the front cut portion thereof projecting beyond the outer convex surface of the cylinder, forming the knives 16, whereby receptacle-openings 18 are formed by the displacement of the metal forming said knives, and admitting the substance being cut to pass through said openings 18 to the interior of 75 the cylinder B, and is discharged rearwardly through its open end 23, this being the leading novel feature of my invention.

In order to more readily discharge the substance being cut from the interior of the cylinder, I provide a suitably-shaped spiral 85 scraper 19, adapted to fit properly into said cylinder, having its small or front end 20 supported by fitting into a socket 21, formed in the upper inner end of the axis of the cylinder 90 which revolves around said scraper, the rear end of which is rigidly attached to the frame of the machine.

When the cylinder is rotated on its axis, 95 the spiral-shaped scraper, being held stationary, fitting the interior surface thereof, withdraws the substance being cut by the knives, which is discharged through the open end 23 of the cylinder.

22 is an inclined concaved receiver or spout 100 located beneath the cylinder B, for the purpose of catching the liquid substance which

escapes therefrom and is discharged at its lower end 14.

24 is a presser-lid for the hopper 8, and is hinged to one of its sides or to one of the 5 clamping-screw rods 6. Said lid is provided with a suitably-constructed spiral spring 25, giving it sufficient power to force the substance beneath the lid down upon the knives of the cylinder, as it is rotated by means of 10 the crank 11, or may be driven by a belt or gear-wheels, if desired, in large-sized machines.

I also provide a series of teeth 26 on the interior of the hopper 8, for the purpose of assisting in holding the substance being cut 15 against the knives of the cylinder.

I am aware that rotary vegetable-cutters have been used prior to my invention, and I therefore do not broadly claim such a construction. 20

Having fully described my invention, what I claim as new and useful, and desire to secure by Letters Patent, is—

1. In a fruit or ice cutter, the combination,

with the frame and hopper and a rotating 25 cylinder provided with integral cutting-knives on its surface and openings in front of said knives, of a spirally-formed scraper fitting the interior of said cylinder and adapted to discharge the material cut by the knives, substantially as described.

2. In a fruit or ice cutter, the combination, with the grooved and apertured front and rear parts 12 and the side portions 5 and rods 6, forming the frame and hopper, of the rotating cylinder mounted in the frame, the inclined concaved chute or spout below the cylinder, the spirally-formed scraper, and the spring-actuating presser-lid hinged to one side of the hopper and normally pressing upon 40 the material in the hopper, substantially as described.

In testimony whereof I affix my signature in presence of two witnesses.

HENRY TAYLOR KING.
